UNITED STATES PATENT OFFICE.

JOHN ECKS, OF MILWAUKEE, WISCONSIN.

CAR-LOADER.

1,072,441.

Specification of Letters Patent.

Patented Sept. 9, 1913.

Application filed December 21, 1911. Serial No. 667,063.

To all whom it may concern:

Be it known that I, JOHN ECKS, a citizen of the United States, and resident of Milwaukee, in the county of Milwaukee and

5 State of Wisconsin, have invented new and useful Improvements in Car-Loaders, of which the following is a description, reference being had to the accompanying drawings, which are a part of this specification.

10 This invention relates to car loaders for loading railway box cars with coal or the like through the usual doorway in the middle of the car and has for its object to provide a conveyer mechanism which may be 15 quickly and easily run through the doorway of the car and projected to one end of the car for carrying the coal from an ordinary chute at the doorway to the end of the car.

20 Another object of the invention is to provide such conveyer with means for automatically raising its discharge end as the pile of coal discharged therefrom increases and also to provide it with means for retracting 25 it from the end of the car as the pile of coal advances.

Another object of the invention is to provide the conveyer with a mounting which 30 will enable it to swing as well as to change its angle of inclination and permit of the coal being discharged at any point in the car.

Another object of the invention is to provide the conveyer with a deflector which 35 will change the direction of movement of the incoming coal so as to discharge it onto the conveyer in the same direction as the movement of the conveyer to relieve the conveyer of wear.

40 Another object of the invention is to provide the car loader with a pivotal mounting which will enable the entire machine to be turned to a position parallel with the car and will enable it to operate upon cars on 45 tracks on either side thereof.

Another object of the invention is to perfect details of construction of car loaders.

With the above and other objects in view the invention consists in the car loader as 50 herein claimed and all equivalents.

Referring to the accompanying drawings in which like characters of reference indicate the same parts in the different views: Figure 1 is a side view of a car loader con-

structed in accordance with this invention 55 in position for delivering coal within a car; Fig. 2 is a plan view thereof; Fig. 3 is a sectional elevation of the car loader with the sliding frame retracted and the conveyer frame swung to a position over the sliding 60 frame, the position of the machine when not in use; Fig. 4 is a detail view on an enlarged scale of the pivotal and swinging mounting for the conveyer frame; Fig. 5 is a transverse sectional view through the conveyer 65 frame on the line 5—5 of Fig. 3; Fig. 6 is a transverse sectional view through the base frame and the sliding frame on the plane of line 6—6 of Fig. 3; Fig. 7 is a detail sectional view showing the pivotal connection 70 for the swinging frames; and, Figs. 8, 9, 10 and 11 are diagrams showing the method of entering the car loader through a car door opening and of manipulating it therein for filling both ends of the car.

75 In these drawings 10 indicates a foundation or support which may be stationary or movable and on which is mounted a spider 11 carrying beveled rollers 12 arranged in a circle to constitute a pivotal bearing together with an upright king bolt 13 in the frame at the center of the circle for a turntable 14 which has a beveled tread bearing on the rollers and a central hub fitting on the king bolt. A pair of channel iron beams 15 80 are securely mounted on the turn table 14 and are connected together at intervals by cross pieces 16 to form a rectangular frame which, to distinguish from other frames in the mechanism, will be referred to as the 85 base frame. A series of standards 17 are carried by the beams 15 of the base frame to form supports for rollers 18, each standard having a pair of such rollers, one higher than the other as seen in Figs. 1 and 3 and 90 one nearer to the middle of the base frame than the other as seen in Fig. 2. These rollers 18 constitute the support for a sliding frame formed by a pair of I-beams 19 and their cross connections 20. The I-beams 19 100 bear upon the lower rollers 18 and have the upper rollers 18 positioned in the space between the upper and lower flanges thereof on the outer side of the frame and riding upon the lower flange to keep the sliding 105 frame from tilting when in its extended position, as shown in Fig. 1. The movements of the sliding frame on its roller bearing

support are produced by a cable mechanism, shown in Fig. 3, a cable 21 being attached at one end to an end of the sliding frame and passing around a pulley 22 on a shaft 23 at 5 the opposite end of the base frame, and then around a drum 24 on a shaft 25 extending across the intermediate portion of the base frame, and then around another pulley 22 on the shaft 23 at the other end of the base 10 frame and then connected at its other end with the opposite end of the sliding frame. The drum 24 is turned by a sprocket chain connection 26 connecting its shaft 25 with a crank handle 27. By turning the crank 15 handle 27 the sliding frame is easily moved in either direction. At one end of the sliding frame the I-beams 19 thereof are connected by heavy cross rods 28 which form the supports for a turntable base 29 which 20 has a turntable 30 mounted on a king bolt 31 standing up from the center of the base 29 and bearing on conical rollers 32 between the beveled bearing surfaces of the base and turntable. At the portion of the sliding 25 frame not occupied by the turntable there is a platform or decking 33 on which the operator may stand. A pair of channel iron beams 34 are secured to the turntable 30 and together with their cross connections constitute 30 a turning frame for swinging the conveyer mechanism from side to side within the car and for turning the conveyer mechanism to any desired angularity with relation to the sliding frame. These channel 35 beams 34 have supporting brackets 35 mounted on them, as best seen in Fig. 4, and rocking frames 36 are pivotally mounted on them by being suspended on stub shafts or studs 37 which project from the brackets 35. 40 The rocking frames 36, as shown in Fig. 4, have rollers 38 at their upper corners which support a conveyer frame formed by a pair of channel iron beams 39 and their cross connections, the rollers 38 fitting in the recesses between the flanges of the beams 39 and having the upper flanges bearing thereon. The cross connections for the conveyer frame are not directly between the beams 39 as said beams form the side guide walls for 45 the conveyer, but cross pieces are in the form of angle iron strips 40 connecting the lower edges of the beams 39 at intervals. Also there are brackets 41 secured to the lower edges of the beams 39 and angle iron strips 50 42 are fastened to the lower ends of the brackets and have a sheet metal decking 43 mounted on them and extending beneath the conveyer the full length and width thereof. At each end of the conveyer there is a roller 55 44 around which a conveyer belt 45 passes, its upper length forming the conveying portion and being supported against sagging by rollers 46 journaled in the brackets 41 and by supporting strips 47 which are 60 secured to the lower edges of the beams 39

with the edges of the conveyer belt bearing thereon.

The sliding movements of the conveyer frame on the pair of swinging frames 36 may be produced in the same manner as 70 with the sliding frame 19, a cable 48 having one end attached to one end of the conveyer frame and passing around a drum 49 on a shaft 50 journaled in the swinging frame 36 and then connected at its other end to the other end of the conveyer frame. The shaft 50 may be turned by means of a crank handle 51, Fig. 1, for accomplishing this 75 sliding adjustment of the conveyer frame and may be locked, as shown in Fig. 4, by a sliding bolt 52 on one of the swinging frames 36 engaging a notched disk 53 on said shaft 50. The lower length of the conveyer belt passes over a pair of pulleys 54 journaled in the swinging frames 36 and around a driving pulley 55 also journaled in said swinging frames on a shaft 56 which carries a gear wheel 57 in mesh with a pinion 58 on a sleeve 59 loosely mounted on one of the studs 37. This sleeve 59 is driven by a sprocket connection 60 from an electric motor 61 or other driving means mounted on the extended ends of beams 34, best seen in Figs. 1 and 2.

The tilting movements of the conveyer frame are produced by worms 62, Figs. 3 and 4, on shafts 63 which are journaled in the beams 34, said worms meshing with worm racks 64 on the lower ends of the swinging frames 36. The worm shafts 63 have worm gears 65 meshing with worms 66 on a shaft 67 journaled in brackets 68 on one of the beams 34 and said shaft 67 has a clutch 69 operated by a lever 70 for coupling it with a sprocket chain connection 71 of sleeve 59 so that the motor driven sleeve will impart motion to the shaft 67 when the clutch is closed to cause the turning of the worm shafts 63 and the swinging of the swinging frames 36 and the conveyer frame mounted on them.

The coal or other material to be loaded in the car is received by the conveyer from any suitable spout 72, Fig. 1, or other delivering means which connects with a hopper or deflector 73 mounted on the swinging frames. This deflector, as shown, comprises oppositely directed chutes with curving bottom walls and curving end walls and a swinging plate 74 on the dividing partition between the two chutes may be changed in its position to make one or the other of the chutes effective, according to the direction of movement of the conveyer belt.

In operation the car loader is entered 125 through the car door opening by swinging the conveyer frame on the sliding frame and by swinging the base frame on its pivotal support and by running the sliding frame through the doorway as shown by the

diagrams in Figs. 8, 9, 10 and 11. From the position of the parts shown in Fig. 3 the conveyer frame is swung until its outer end enters the car door opening, as shown in Fig. 8. Then by turning the base frame 5 on its pivotal support and also turning the conveyer frame on its turntable the base frame is swung to a position at approximately a right angle to the car while the conveyer frame enters through the car door 10 opening to the other side of the car, as shown in Fig. 9. Then the sliding frame is moved upwardly through the car door opening until the turntable 30 thereon is 15 near the center of the car and the conveyer frame reaches to the end of the car. Now the machine is ready for loading the car and the coal or other material fed to the hopper or deflector 73 is directed by the hinged 20 plate 74 to that chute thereof which leads in the direction of the travel of the conveyer belt so as to deliver the coal onto the conveyer belt by which it is carried to the end of the car. At the beginning of the 25 loading operation the conveyer frame is tilted downwardly and as the pile of coal at the end of the car increases in size the conveyer frame may be changed in its angle of inclination by the manipulation of the 30 clutch lever 70, such clutch lever being preferably thrown to close the clutch so that the change in angularity of the conveyer frame will be continuous and automatic until the pile of coal is as high as desired, the conveyer frame having been 35 gradually shifted from a descending position to an ascending position. As the loading progresses the conveyer frame may be retracted and when one end of the car is loaded it is not necessary to further change the angularity of the conveyer frame, but the latch 52 is released and the shaft 50 is turned to slide the conveyer frame to the other end of the car and the hinged plate 40 45 74 of the hopper or deflector is swung to the other side and the motor is started in operation, but in the reverse direction. The loading of the other end of the car is accomplished in the same manner as above 50 described and when this is completed the car loader is withdrawn from the car by the reversal of the operation by which it was entered. During the filling the conveyer frame may be swung on its turntable 55 from side to side so as to reach every part of the car.

By means of this invention the loading of box cars with coal and the like may be quickly and easily accomplished by reversing 60 the position of the hopper or deflector 73. The divided hopper or deflector enables the coal to be delivered to the conveyer belt in the direction in which the conveyer belt is run when filling either end of the car and thus materially reduces the wear upon the 65

conveyer belt. The machine being capable of occupying a position parallel with the car enables the tracks to be placed close together. The metal decking 43 serves to catch such coal as may fall from the conveyer belt and prevent its being taken along with the return portion of the conveyer belt. 70

What I claim as new and desire to secure by Letters Patent is:

1. A car loader, comprising a pivotally mounted base frame, a sliding frame thereon, a conveyer frame pivotally and slidably and tiltably mounted on the sliding frame, and a conveyer on the conveyer frame. 75

2. A car loader, comprising a turn table, a base frame thereon, upper and lower rollers on the base frame, a sliding frame mounted between the upper and lower rollers to move slidably with relation to the base frame, pulleys on the ends of the base frame, a cable attached to the ends of the sliding frame and passing around the pulleys, a suitably operated drum on the base frame around which the cable also passes, 80 85 and a conveyer pivotally mounted on the sliding frame.

3. A car loader, comprising a pivotally mounted base frame, a sliding frame slidably mounted thereon, a turntable on the sliding frame, a support on the turntable, a swinging frame pivotally mounted on the support, and a conveyer slidably mounted 90 on the swinging frame. 95

4. A car loader, comprising a pivotally mounted base frame, a sliding frame thereon, a turntable on the sliding frame, a support on the turntable, a swinging frame pivotally mounted on the support, a segmented worm gear on the swinging frame, a 100 suitably driven worm on the support meshing with the segmented worm gear, a conveyer frame slidably mounted on the swinging frame, and a conveyer on the conveyer frame. 105

5. A car loader, comprising a pivotally mounted base frame, a sliding frame thereon, a turntable on the sliding frame, a support on the turntable, a swinging frame pivotally mounted on the support, a conveyer frame slidably mounted on the swinging frame, a suitably operated drum on the swinging frame, a cable connected to the 110 ends of the conveyer frame and passing around the drum, and a conveyer on the conveyer frame. 115

6. A car loader, comprising a pivotally mounted base frame, a sliding frame thereon, a turntable on the sliding frame, a support on the turntable, a swinging frame pivotally mounted on the support, rollers on the swinging frame, a conveyer frame slidably mounted on the rollers, means for moving the conveyer frame on the rollers, pulleys 120 on the end of the conveyer frame, a driving 125 130

pulley on the swinging frame, a conveyer belt passing around the pulleys on the conveyer frame and around the driving pulley, rollers on the conveyer frame for supporting the conveyer belt at intermediate points, and flanges on the conveyer frame for supporting the edges of the conveyer belt.

In testimony whereof, I affix my signature, in presence of two witnesses.

JOHN ECKS.
